SWITCH

Robert K. Winning, Wauwatosa, Wis., assignor
to Clum Manufacturing Company, Milwaukee,
Wis., a corporation of Wisconsin

Application September 12, 1934, Serial No. 743,675

10 Claims. (Cl. 200—8)

This invention relates to improvements in switches.

It is the object of the invention to provide a novel and simple form of self-centering switch in which a single spring serves to return to a central neutral position a switch actuator and contactor which is movable in each of two directions from that position to close different circuits.

It is my further object to provide an arrangement whereby the number of switch parts is minimized and their assembly facilitated through the use of a novel and simple switch organization.

In the drawing:

Figure 1 is a view of an improved switch mechanism embodying this invention as it appears with the cover of its casing removed.

Figure 2 is a view of the mechanism in section in the plane indicated at 2—2 in Figure 1.

Figure 3 is a detail view illustrating in perspective the relatively separated component parts which move in the operation of the switch.

Like parts are identified by the same reference characters throughout the several views.

The switch casing comprises a cup-shaped casing member 4 having a central opening about which an annular flange 5 is formed for connection with a bracket 6. The casing cover 1 has a registering opening provided with a like flange at 8. The rivets 9 and 10 hold the cover and the cup-shaped casing member together and also serve as stops for the spring 11 and the contact actuator 12, as hereinafter described.

Journalized in the flanges 5 and 8 and exposed in the casing openings, are the reduced end portions 14 of a tubular trunnion member 15 having a diametrical slot at 16. The operating shaft 17 is receivable into either end of trunnion 15 and is provided with a keyway 18 adapted to be registered with slot 16.

The contact actuator 12 may comprise a piece of dielectric material formed to provide spring engaging arms 19 and 20 so joined with the plate-like body of the actuator 12 as to provide rests at 21 into which the rivet pins 9 and 10 are receivable to permit of the oscillatory movement of the actuator within predetermined limits. The intermediate portion of the actuator is provided with a large opening at 23 which corresponds in diameter to the trunnion 15 but into which project the relatively long and short fingers 24 and 25 respectively, these fingers being preferably stamped integrally with the actuator plate 12. Both of these fingers are receivable into the diametrical slot 16 of trunnion 15. The longer finger 24 is of sufficient length so that it passes through the slot 16

of the trunnion into the keyway 18 of the operating shaft 17. Thus the actuator 12 receives motion directly from the operating shaft but serves also to key the shaft, trunnion and actuator together so that these parts rotate as a unit.

The spring 11 comprises a flat strip of spring metal maintained under a predetermined initial tension by the relation of the rivet pins 9 and 10 to the trunnion 15. It will be noted that the lower surfaces of the rivet pins are in a plane which is below the upper surface of the trunnion member 15. Thus when the spring strip is inserted over the trunnion and beneath the rivet pins as shown in Fig. 1, it will be flexed and will thereby be caused to offer a more substantial opposition to the movement of the actuator 12 than would otherwise be the case. The length of the arms 19 and 20 is such that when the spring is inserted as above described the end of each arm will be immediately adjacent one end of the spring, to act upon the spring immediately following the initial oscillation of the actuator in either direction. Crystallization of the spring metal is avoided by the fact that the spring is flexed in the same direction by the movement of the actuator in either direction.

Inasmuch as the spring is under initial distortion and always tends to seat itself against one or the other of the rivet pins 9 or 10, upon being displaced therefrom, it follows that the spring will always tend to maintain the device centered and it cannot become distorted in such a way as to tend to hold the actuator off center. As soon as the actuator is returned to center it is relieved of all spring pressure.

The casing carries suitable fixed contacts 27, 28 and 29 in its periphery. These contacts are suitably insulated from the casing as shown in Fig. 2 and are provided with exterior terminal screws.

The moving contactor comprises a contact spring 30 slightly arched with its ends in pressure engagement with the inner surfaces of the dielectric segments which are fitted to the interior of the casing about the contacts. The contactor lies substantially upon a minor chord of the casing and hence, in the neutral position of the actuator, is adapted to span the contact 29 as shown in Fig. 1.

The contactor is marginally notched at 32 (Fig. 3) and the web portion 33 between the notches is engaged in a notch 34 of contact carrier 35. The lower extremity of the actuating plate 12 and the upper portion of the contact carrier 35, are respectively notched, as best shown

in Fig. 2, so that the carrier 35 is firmly interlocked with the actuator 12 against either axial or angular movement with respect thereto. The pressure of the contactor 30 not only maintains its end portions in effective operative engagement with the contacts encountered thereby during its oscillation, but also maintains the contactor fixed in the notch of the contact carrier and holds the contact carrier firmly engaged and interlocked with the actuator.

The fact that the contact actuator 12 is made of dielectric material adequately insulates the contactor 30 from the shaft and switch casing. The carrier 35 may be metallic. It is restrained 15 from contact with the walls of the casing by the actuator plate 12, which in turn is prevented from axial movement by means of the spring 11.

It will be noted that the spring is closely fitted between the back of the casing and its cover, and 20 is slotted at 37 to receive the actuator 12. Thus, when all the parts are assembled as described, the operating shaft 17, the trunnion member 15, the actuator 12, the contact carrier 35, and the contactor 30 are all movable as a unit about the axis 25 of shaft 17. The trunnion member 15 and parts mounted therein within the casing are all permanently assembled with the casing. The operating shaft 17, however, is not fastened within the casing and may be operatively moved axially to 30 and from engagement with the switch mechanism.

It is particularly desired to call attention to the multiplicity of functions performed by the several parts of this device, whereby the number of parts has been greatly reduced as compared with other 35 switches having like functions.

The rivet pins 9 and 10 not only hold the casing cover to the casing cup, but also serve as stops for the actuator 12, and also serve to maintain the spring 11 under a predetermined minimum pressure and to relieve the switch actuator of pressure 40 when the actuator is centered as shown in Fig. 1.

The spring 11 not only serves to center the contact actuator and the contactor following each 45 switching operation, but also serves to position the actuator 12 against axial movement within the switch casing, and the actuator 12 serves not only to transmit motion from the trunnion member 15 to the contactor, but also serves to pick up spring 11 when the actuator is moved in either 50 direction from center and is further adapted to key the trunnion member to the operating shaft when the operating shaft is inserted therein.

The contactor 30 serves not merely to connect the contact 29 alternatively with contacts 27 or 55 28, but also serves, through its reaction pressure, to maintain the contact carrier 35 from being interlocked both with the actuator 12 and the contactor spring 30.

I claim:

60 1. In a switch, the combination with an oscillatable member, of a contact actuator carried by said member and oscillatable therewith, a spring element disposed transversely of said member, a pair of stops maintaining said spring element under pressure and comprising means limiting the movement of said member, and arms carried by said member and adapted in the intermediate position thereof to lie closely adjacent said spring means and adapted to move said spring means 65 from said stop in either direction of oscillation of said actuator from said position.

70 2. The combination with a slotted member mounted for oscillation, of a contact actuator provided with a lug fitted to said slot and axially 75 movable therein for the assembly of the parts

and a flat spring adapted to act on said actuator, and means constraining said spring against displacement, said spring having a slot in which said actuator is confined whereby said actuator is positioned in the slotted member.

75 3. In a switch, the combination with an oscillatory member, of a pair of stop pins spaced at opposite sides of said member, a distorted spring strip between said member and pins having its ends biased into pressure engagement with said pins, and an actuator carried by said member and oscillatable between said pins, said actuator having arms alternatively engageable with free end portions of said spring strip in a direction to increase the distortion of said strip upon movement of said actuator in either direction of oscillation from a predetermined central position, whereby such movement is resiliently opposed by said spring strip.

10 4. In a switch, the combination with a casing, of a trunnion member journaled for oscillation therein and provided with a slot, an actuator apertured to receive said trunnion member and having a lug portion receivable in the slot thereof, contact means carried by said actuator, 15 and an operating shaft provided with a keyway and receivable into said trunnion member with its keyway in registering engagement with the end of the lug of said actuator.

15 5. In a switch, the combination with a casing, 20 of a trunnion member journaled for oscillation therein, a contact actuator splined to said trunnion member, a flat spring disposed transversely of said trunnion member and slotted to receive said actuator, arms carried by said actuator and lying adjacent the ends of said spring in an intermediate position of said actuator, whereby to pick up said spring upon movement of said actuator in either direction from said position, stop means against which the ends of said spring are 25 engaged in the intermediate position of the actuator, and a contactor connected with said actuator and adapted to be moved in either direction from said position against the resilient opposition of said spring.

25 45 6. In a switch, the combination with a casing provided with relatively fixed contacts adjacent its inner periphery, of a trunnion member journaled for oscillation adjacent the center of the casing and axially slotted, a contact actuator mounted on said trunnion member and provided with lug means engaged in the slot thereof, a spring strip slotted to receive said actuator and bearing on the top of said trunnion member, pin means against which the end portions of said 30 spring strip are engaged under pressure, arms carried by said contact actuator and disposed in an intermediate position thereof in close proximity to the free end portions of said spring strip, a spring contactor disposed substantially 35 on a minor chord of said casing and of such span as to be adapted to connect the contacts thereof upon displacement from the intermediate position of said actuator, and means connecting said contactor with said actuator to partake of 40 the movement of said actuator and trunnion member in opposition to said spring strip in both directions of oscillation.

45 55 7. The combination with an oscillatable contact actuator having arms projecting oppositely 70 along its path of oscillation of a central support, a spring strip carried thereby and having end portions disposed respectively in the path of movement of said arms and engageable by the respective arms in the oscillation of said actu- 75

- ator, the ends of said strip being resiliently yieldable under the thrust of the respective arms in the direction of oscillation of the actuator, and stop means with which the ends of said strip are normally engaged under an initial bias in said direction and in positions normally free of said arms, whereby said arms pick up one or the other end of said strip in either direction of oscillation to increase the deflection of said strip.
- 5 8. In a switch, the combination with means supporting stationary contacts in arcuate series, of a contact actuator oscillatable about the axis of the arc on which said contacts are disposed, means carried thereby provided with fingers spaced at opposite sides of said arc, and a resiliently flexible contactor notched to receive said fingers in its intermediate portion and having its free end portions resiliently biased for engagement with the respective contacts in the course 10 of its movement in said arc.
- 15 9. In a switch, the combination with a casing providing terminal contacts in an annular periphery, of a contactor oscillatable substantially about the axis of said annular periphery, contact means carried by said actuator and movable about the interior periphery of said casing to bridge the terminal contacts therein, a spring extending across said axis and having its end portions free, means supporting the intermediate portion of the spring, stops maintaining said spring under tension across said supporting
- 20
- 25
- 30

means, said stops being located intermediate the central portion and the respective ends of the spring, and arms connected with said actuator and respectively disposed outside of said stops in positions to engage the respective ends of the spring upon oscillation of the actuator in either direction about said axis.

10. In a switch, the combination with a casting or annular form provided in its periphery with spaced terminal contacts in arcuate series, of fulcrum means adjacent the center of the casing, a plate-like contact actuator mounted at its intermediate portion upon said fulcrum means and provided at one side thereof with a substantially radial slot and at the other thereof with arcuately extending arms, a contact carrier having a slotted portion interlocked with the slotted portion of said actuator and provided with fingers spaced at opposite sides of the series in which said contacts are disposed, a spring contactor having an intermediate portion engaged by said fingers and having its free ends biased for engagement with the contacts in said series, stops at either side of the path of oscillation of said actuator, and a spring bent across said fulcrum means and engaged under tension by said stops, the ends of said spring being free and exposed in the path of movement of said arms for engagement by the respective arms upon oscillation of the actuator in either direction.
